UNITED STATES PATENT OFFICE.

AUGUSTUS M. HALSTED, OF RYE, NEW YORK.

INCUBATOR.

SPECIFICATION forming part of Letters Patent No. 236,886, dated January 25, 1881.

Application filed September 16, 1879.

To all whom it may concern:

Be it known that I, AUGUSTUS M. HALSTED, of Rye, county of Westchester, State of New York, am the inventor of an Improved Incubator Apparatus, of which the following is a full, clear, and exact description, reference being had to the accompanying drawings, forming part of this specification.

My invention relates to an apparatus for the incubation or hatching of eggs; and it consists in the devices and their combination hereinafter particularly described, and more at length recited in the claims, whereby a durable apparatus, and one not liable to be affected in its parts by the variations in temperature to which it is subjected, is constituted, and whereby the variations in temperature in the hatching-chamber may be automatically limited to a certain predetermined degree, and a substantially equable temperature may be maintained at all times in the hatching-chamber, and whereby the degree of heat to be maintained in the hatching-chamber may be regulated or altered, as may be desired, from the exterior of the apparatus, and without disturbing the said chamber or its contents, or allowing the contact with its contained heated atmosphere of the external air, while at the same time the perfect ventilation of the hatching-chamber is secured, and whereby the atmospheric conditions and temperature of the hatching-chamber with relation to the contained eggs may be made to correspond accurately to the similar conditions demanded and afforded by nature for the best results in incubation, all as hereinafter set forth.

Figure 1, Sheet 1, is a front elevation of an apparatus embodying my invention. Fig. 2, Sheet 1, is a plan of the same. Fig. 3, Sheet 2, is a vertical central sectional view of the apparatus on the line $x-x$ of Fig. 4. Fig. 4, Sheet 2, is a horizontal sectional view of the apparatus on the line $y-y$ of Fig. 3. Fig. 5, Sheet 3, is an end elevation of the apparatus, showing the water-boiler and its lamp, and the devices employed to regulate the temperature in and secure the ventilation of the hatching-chamber. Fig. 6, Sheet 3, is an elevation of the opposite end of the apparatus. Figs. 7 and 8, Sheet 4, are side and plan views, in detail, of the thermostatic bar and its regulat-

ing devices which I employ in my apparatus. Figs. 9 and 10, Sheet 4, are plan and sectional views, respectively, of the peculiar lamp-burner and the mechanism for raising and lowering the flame which I employ in my apparatus, but which burner and said mechanism I do not intend herein to claim as new, reserving the same to be made the subject of a separate application for Letters Patent to be made hereafter. Fig. 11, Sheet 4, is an enlarged view, in detail, of the devices employed to raise and lower the flame of the lamp of the boiler.

A is the hatching-chamber, which is preferably arranged in the lower part of the apparatus, as shown, immediately beneath the heating tank or device B. In the hatching-chamber A is the tray a , which may be passed into or removed from said chamber through the door a' , said door being preferably glazed, as shown, to allow of the inspection of the chamber from the outside of the apparatus without opening the door. Beneath the tray a , and within the chamber A, is arranged the water pan or reservoir a^2 , to be filled with cold water, between the tray and pan there being placed the screen a^3 . The bottom of the tray a should be so constructed as to allow the free circulation of the air through it, and this is preferably accomplished by having said bottom formed of transverse rods extending from side to side of the tray-frame, as shown, and said rods should also be placed at such a distance apart that an egg will rest between two adjacent rods, so that the eggs placed in the tray will not roll about, but will be held in position on the tray-bottom. I also find it desirable to have the said bottom hollowing or concave in form—that is, lower in the center of the tray than at the ends—inasmuch as the heat radiated from the surface of the tank or heater B is somewhat greater at the center of the chamber than at the ends, and as it is desirable to have the heat felt at the same degree throughout the tray. In this tray it is intended that the eggs to be incubated should be placed, and I find it desirable that a layer of cotton or linen cloth, as shown at a^4 , Fig. 3, should be interposed immediately under the eggs, and between them and the water-pan a^2 below the tray.

It is evident that by means of the construc-

tion and arrangement of the hatching-chamber as described I am able to most closely realize those conditions demanded by nature for the best results in incubation—namely, a warm damp atmosphere on the under side of the egg, as when the hen sets upon a nest made on the ground, and a warmer dry atmosphere at the upper side of the egg, as is produced by the contact of the egg with the hen's body on the nest. My apparatus being in operation, the water in the pan a^2 evaporates, and thus will cause the atmosphere in the lower part of the hatching-chamber beneath the tray to be moist, and this moist atmosphere will be felt upon the under side of the eggs in the tray, while the upper part of the hatching-chamber above the tray will be filled with a warmer dry atmosphere by the radiation from the heater B, immediately over the tray, which will be felt on the upper side of the eggs. As the chicks are hatched out, the screen a^3 prevents them from falling into the water-pan below. The eggs should, of course, be turned in the tray at proper intervals of time, and this is readily accomplished by drawing out the tray for the purpose and then replacing it.

The heating device which I prefer to employ is a tank, B, placed directly over the hatching-chamber, so that from its under surface is radiated the heat required in the process of incubation. Water is heated in the boiler b, and circulates from thence through the pipe b^1 and its branch pipes b^2 and b^3 into the tank B. The pipes b^2 and b^3 are arranged as shown in Figs. 3 and 4, passing through the tank B, and around the inside thereof to the opposite end thereof, and there extending across to opposite sides and discharging into the tank at opposite corners of the end farthest from the source of supply. A pipe, b^4 , leads from the end of the tank opposite to that at which the supply-pipes b^2 and b^3 discharge their heated water back into the boiler, as shown. I am by means of this construction of parts enabled to obtain the full effects of the heat imparted to the water in the boiler, and also to maintain a perfect circulation of the water from the boiler through the tank and back into the boiler. At b^5 is an orifice 50 for filling the tank B with water, and at b^6 is an air-vent. A glass gage, b^7 , set in the wall of the tank, as shown in Fig. 1, enables the operator to observe the height of the water in the tank.

The boiler b, which I employ, having been heretofore used in connection with incubators, I will not particularly describe it, as it is fully shown in the drawings; but the lamp by means of which the heating of the water in the boiler is accomplished contains improvements which I shall hereinafter describe.

It is well known that to secure the incubation of eggs the temperature of the surrounding air must be maintained at a given degree, and that a variation from this required temperature will be fatal to successful hatching of the chicks. It is also necessary that the

air about the eggs should be kept pure and free from noxious gases. To secure these conditions I employ the following devices:

Within the chamber A, or under the influence of the temperature thereof, I place a thermostatic bar, D, as shown in Fig. 3, and in detail enlarged in Figs. 7 and 8. This bar I prefer to construct of a metal strip, d, secured upon a vulcanized rubber plate or strip, d^1 . To secure the best results, it is preferable to place this bar D over the egg-tray and immediately beneath the radiating-surface of the heater B, as is shown in the drawings; and when the bar is thus arranged I find it desirable to secure the strips of which the bar is composed together by means of rivets or other such fastenings, as shown, placed upon each edge of the metal strip throughout the length thereof. By this means I am able to overcome the objectionable tendency in the bar to bend edgewise, as well as flatwise, when influenced by the heat radiated from the heater B, such edgewise bending occurring when the two strips are secured to each other by a single row of rivets, as is usual in the construction of these bars. One end of this bar is rigidly secured to a lever, d^2 , (see Figs. 7 and 8,) which is pivoted to one side of a plate, d^5 , so as to swing laterally thereon, said lever being provided with the spring d^6 , acting upon one arm, and the thumb-screw d^7 , turning in said plate and impinging on the other arm. Upon the opposite side of said plate d^5 is formed the sharp or knife-edge projection d^8 , its edge being at right angles to the axis of the pivot of the lever d^2 , and from said plate extend the rods or bolts d^9 and d^{10} , above and below the said projection d^8 , respectively, and furnished with thumb-nuts, as shown. These described devices I find are to be preferably employed to adjust the thermostatic bar, both vertically and horizontally, in the chamber A. The plate d^5 is placed so that its projection d^8 impinges upon the inner face of the wall of the chamber A, at one end thereof, as shown in Fig. 3, and the screw d^7 and the bolts d^9 and d^{10} extend through the said wall to the exterior of the apparatus, said bolts thus serving to hold the fixed end of the bar in position. The bar reaches the length of the chamber A, and its free end, or an arm, d^{11} , fixed thereon, extends through a slot, d^{12} , in the opposite wall, as shown.

At E is a ventilating shaft or flue leading from the chamber A upward into the external air. In this flue is the damper e on the axial shaft e', which extends outward from the apparatus on the same end as the free end of the bar D, as shown. Now it is evident that if, when the air in the chamber A becomes heated to a temperature higher than that necessary for the incubation of the eggs, the damper is swung on its shaft so as to open the flue E, and is then swung so as to close said flue and keep it closed while the air in the said chamber is at the proper temperature for the incubation of the eggs, substantially equable tem-

perature may be at all times maintained in the chamber A.

It is well known that a thermostatic bar such as I have herein described will be flexed or bent more or less, as the temperature to which it is exposed or subjected is higher or lower, and that such a bar is exceedingly sensitive to changes in the temperature; and it is evident that, one end of my described bar being held rigidly by the devices set forth, the free end will be caused to move horizontally by the flexing or curving of the bar as the changes of temperature in the chamber A occur. This movement of the free end of the bar D in one direction, when the temperature in the chamber A rises above the desired degree, I utilize to open the damper e in the flue E, and the movement of said end of the bar in the opposite direction, when the temperature in said chamber has fallen to and remains at or below the desired degree, I utilize to close and hold shut the said damper by means of suitable transmitting mechanism intermediate to the free end of the bar D and the damper e. I find that the following-described mechanism is well adapted for this purpose, and I prefer to employ it: A lever, F, is pivoted to a suitable plate, f, upon the exterior of the apparatus, as seen plainly in Fig. 5. In the end of one arm of this lever is a slot, f', which engages the free end d¹¹ of the bar D, which projects through the slot d¹² in the wall of the apparatus, as before set forth. The end of the other arm of the lever carries two fingers, f² and f³, which are turned or inclined toward each other, with a space or opening between their adjacent tips or ends, as seen in the drawings. Upon the end of the shaft e' of the damper e is a reel, e², from the perimeter of which project the alternate pairs of diametrically-opposite radial arms e³ and e⁴, upon the ends of which are the angular fingers e⁵, the pair of arms e³ being longer than the pair e⁴, so that the finger on either of the arms e³ may engage the finger f² of the lever F, and the finger on either of the arms e⁴ may engage the finger f³ of said lever. A cord is wound upon the reel e², and its free end passes over a pulley or block, e⁶, and has attached to it a weight, e⁷, as shown.

Now it is evident that the bar D may be so adjusted vertically by means of the bolts d⁹ and d¹⁰, and horizontally by the thumb-screw d⁷, that when the exact temperature desired exists in the chamber A the free end of the flexed bar D will hold the lever F in position where the finger f² of said lever engages the finger upon the end of one of the long arms, e³, and that, these said arms e³ being properly placed on the shaft e' with relation to the damper e, the parts being in the positions indicated, the damper e will be closed. When the temperature rises in the chamber A, the further flexing of the bar D will cause its end d¹¹ to swing the lever F, so that the fingers of the arm e³ will escape from the finger f² through the space between the ends of the fingers f²

and f³, and the shaft e' being thus released, the weight e⁷ will operate to revolve the said shaft, and thus open the damper e. One of the arms e⁴ will, by its finger e⁵, now, as the shaft e' rotates, come in contact with the finger f³ of the lever F, and will thus stop the shaft's rotation at that point and hold the damper open. As the temperature in the chamber A falls to the desired point the bar D will gradually recoil, carrying the lever F with it, until said lever is swung backward into the position where the finger of the arm e⁴ will escape from the finger f³ through the space between the said fingers f³ and f², as aforesaid, when the shaft e' will rotate, closing the damper, and the finger of the other arm, e³, of the pair will engage the finger f² of the lever F, stopping the rotation of the shaft and holding the damper closed. I am thus enabled, by means of the bar D, placed in the heated chamber A, to utilize the variations of temperature in said chamber to automatically open and close the damper e by means of a suitable transmitting mechanism intermediate to the bar and damper, whereby the variations in the temperature of the said chamber may be confined within certain predetermined and desired limits, and consequently a substantially equal temperature in the said chamber is maintained, while the thorough ventilation of the chamber is secured. The bar D will operate as set forth when so placed as to be influenced by the variations in temperature in the chamber A, even though it may not be placed immediately within the said chamber.

It is also evident that I am able to secure the adjustment of the bar D, and to control and regulate the degree of heat in the chamber A, wholly from the exterior of the apparatus, by means of the bolts d⁹ and d¹⁰ and the thumb-screw d⁷ and their attached devices, the said bolts and screws reaching through the wall to the outside of the machine, as shown. The disturbance of the eggs in, or atmosphere of, the chamber A is thus wholly avoided. A thermometer, T, which projects into the chamber A, has its scale exposed to view above the apparatus, as shown.

It is desirable that the heat applied to the boiler should be reduced or checked during the time that the damper e is open and the temperature in the chamber A is falling. To accomplish this I find it preferable to employ the following devices, in connection with the devices described for opening and closing the damper e: A lever, G, is pivoted to a suitable plate, g, on the exterior of the apparatus, as shown. Upon the end of this lever is the shoulder or projection g', which is arranged to engage one of the pins or studs e⁸, which project at right angles from the perimeter of the reel e², and are diametrically opposite to each other, and in line, respectively, one with each of the arms e⁴. A rod, g², connects the lever G with a lever, h, that operates to move a sleeve, h', about the wick of the lamp-burner, to be hereinafter described. The devices are

thus so constructed and arranged that when the bar D has released the shaft e', so that the damper in flue E is swung open, the shoulder or projection g' is released by the rotation of the said shaft from engagement with one of the pins, e⁸, and, falling by its own weight, causes the lever h to push the sleeve h' on the burner up about the wick, and thus reduce the flame of the lamp. When the bar D has caused the shaft e' to be again released, and the damper in the flue E is closed, the shoulder g' is, by the rotation of the shaft, caused to engage the other pin e⁸, and the lever G is thus raised, causing the lever h to pull the sleeve downward on the wick, and thus restoring the flame to its full force.

Instead of raising and lowering the sleeve about the wick, the rod g² may be arranged to, by suitable devices, move the wick itself up and down in the burner, and thus raise and lower the flame.

At H is seen the lamp which I employ in connection with the boiler. To the reservoir of the lamp is fixed an upwardly-reaching arm, h². This arm carries a hinge-rod, h³, which fits into a corresponding socket or sleeve, h⁴, on the side of the apparatus. Upon the end of the arm h² is a lug, h⁵, which is arranged to abut or fit against a lug, h⁶, fixed on the wall of the apparatus. A thumb-screw, h⁷, passes through these two lugs. By means of these devices so arranged, when the thumb-screw h⁷ is withdrawn from the lug h⁵, the lamp will be lowered so that the burner will wholly escape from the chimney in the boiler, and may be swung on its hinges, and thus may be conveniently filled, trimmed, &c., or it may be wholly detached from the apparatus, while, when it is swung back into place, the burner will be drawn into close contact with the lower rim of the chimney by tightening the screw h⁷. Upon the burner of my lamp, and about the wick-holder, I place a sleeve, h', (see Figs. 9 and 10,) upon diametrically-opposite sides of which are the pins or studs h⁸. A single piece of wire has one end inserted in an orifice in the burner-frame, as at h⁹, and is then bent at right angles and then turned to form a loop, h¹⁰, about one of the pins h⁸, and then carried around the sleeve to the opposite side, and there turned to form a loop about the other pin, and thence bent at right angles and passed through an orifice in the burner-frame, as at h¹¹, beyond which it is again bent to form the hereinbefore-named lever h. It is evident that by depressing the end forming the lever h the sleeve will be carried upward about the wick, and by again raising said end the sleeve will fall downward. It is not my intention to claim herein this novel burner and sleeve and actuating devices; but I reserve the same to be made the subject-matter of a separate application for Letters Patent.

In fabricating my apparatus I construct it wholly of metal, the walls of the hatching-chamber and heating-tank being of two thicknesses of metal, with an interposed non-heat-conducting material, as shown at m. I thus constitute an apparatus which is thoroughly durable, and which will not be affected by the changes in temperature to which its parts are subjected.

I do not intend to claim herein the peculiar structure of the improved thermostat shown, but reserve the same as the subject of a separate application for Letters Patent.

What I claim, and desire to secure by Letters Patent, is—

1. In an incubator apparatus, the hatching-chamber having a suitable heating device above and a water-evaporator pan below the egg tray or holder, having the concave bottom described, together with a wall or layer of cloth, as described, so placed as to be beneath the eggs held by the tray, as and for the purpose set forth.

2. In an incubator apparatus having the hatching-chamber A and heater B, arranged as described, the egg-tray a, having the concave bottom on which the eggs rest, as and for the purpose specified.

3. In an incubator apparatus, the combination, with the hatching-chamber having a suitable heating device, of a thermostatic bar, D, held rigidly at one end, its free end engaging the slotted lever F, carrying fingers f² f³, together with damper e on shaft e', having weighted reel e², carrying the alternate pairs of diametrically-opposite radial long and short arms e³ and e⁴, respectively, as and for the purpose specified.

4. In an incubator apparatus, the combination, with the hatching-chamber having heater B and a thermostatic bar, D, of the lever G, with its rods g², projecting shoulder-piece g', arranged to engage pins e⁸ and reel e², together with mechanism for transmitting the motion of the free end of the bar D to said reel, as and for the purpose specified.

5. In an incubator apparatus having hatching-chamber and its suitable heating device, the thermostatic bar D, fixed at one end to the spring-lever d², which is pivoted to plate d⁵, having projection d⁸ on its reverse side, impinging on inner surface of the chamber-wall, together with thumb-screw d⁷ and bolts d⁹ and d¹⁰, extending from said lever and plate, respectively, through said wall to the exterior of the apparatus, as described, and for the purpose specified.

AUGUSTUS M. HALSTED.
